(57) **CLAIM**

The ornamental design for plastic baseboard heater device, as shown and described.

DESCRIPTION

FIG. 1 is a side, perspective view of a plastic baseboard heater device showing our new design;

FIG. 2 is a front elevational view thereof;

FIG. 3 is a left side elevational view thereof;

FIG. 4 is a right side elevational view thereof; and,

FIG. 5 is a top plan view thereof.

The broken lines shown in the Figures are included for the purpose of illustrating the environmental structure and form no part of the claimed design.
